BEVEL METHOD SAWING

Edward P. Stamm, Portland, Oreg.

Application January 12, 1942, Serial No. 426,501

2 Claims. (Cl. 144—309)

This invention relates to an improved method of sawing logs into lumber.

An object of this invention is to provide an improved means whereby both rectangular and bevelled lumber may be cut from a log with a minimum amount of waste and a minimum amount of handling of the log and the lumber.

Another object of this invention is to provide an improved method of cutting logs, which is designed particularly for cutting logs so that the grain in the lumber is substantially perpendicular to the opposite faces thereof.

A further object of this invention is to provide an improved method of sawing or cutting logs into lumber which will permit the cutting of the lumber in such a manner that the knots will extend substantially lengthwise of the opposite faces of the boards instead of at a more nearly perpendicular position with respect to the faces of the boards.

A further object of this invention is to provide an improved method of sawing and handling lumber which will permit a small mill using light equipment to cut the logs into the desired boards without the use of expensive equipment.

A further object of this invention is to provide an improved method of radially cutting a log into lumber so as to provide bevelled or tapered side strips with the grain of each strip substantially perpendicular to the opposite faces of the board.

A further object of this invention is to provide an improved method of cutting boards from logs whereby a greater number of boards will have the grain substantially perpendicular to the faces of the boards than is at present the case, and in carrying out this method, the perpendicular or vertical grain is obtained without wastage except for the waste caused by the saw blade moving through the lumber.

To the foregoing objects and others which may hereinafter appear, the invention consists of the novel construction, combination and arrangement of parts as will be more specifically referred to and illustrated in the accompanying drawings, but it is to be understood that changes, variations and modifications may be resorted to which fall within the scope of the invention as claimed.

In the drawings:

Figure 1 is a detail end elevation of a log showing the manner of cutting the log according to the present method.

Figure 2 is an end elevation of a log showing the method of cutting the log into rectangular lumber under the practice heretofore obtaining.

Figure 3 is an end elevation of a log showing

diagrammatically the positions of the knots in the log, and the manner in which these knots are cut so as to position them lengthwise of the opposite faces of the boards.

Figure 4 is a detail end elevation of a log mounted on a radial sawing apparatus whereby bevelled boards may be cut therefrom, and

Figure 5 is an end elevation showing the manner of cutting the triangular heart section from the log.

Referring to the drawing the numeral 10 designates generally a log which is shown in end elevation. When the log 10 is initially brought into the mill for cutting into boards, this log 10 is cut first into two half sections, and then each half section is cut into quarters 11, 12, 13, and 14. Where it is desired to cut only one board of suitable thickness from a quarter section, such as section 11, the quarter section is mounted on the saw carriage with one face thereof confronting the saw which is preferably a band saw, and a vertical cut 15 is made through the log section 11. The remaining sector shaped section is then mounted and supported on the saw carriage so that a triangular board 16 is cut through the right angular faces of the log. This provides a truncated sector shaped log body 17 as shown in Figure 4.

The truncated sector shaped section 17 shown in Figure 4 is then mounted on a radial log supporting device 18. The log section 17 is mounted on the radial sawing device 18 with one flat face 19 thereof resting on the upper side of the sawing device 18 and the other flat or right angularly disposed face 20 disposed in a substantially vertical position and at a point forwardly of the axial center 21 of the radial sawing apparatus.

The radial apparatus 18 is then progressively raised, and the saw carriage moved lengthwise past the saw in order to cut wedge shaped or bevelled boards 22, shown in Figure 1. The radial log supporting apparatus 18 is progressively raised to bring successive portions of the log section 17 into cutting position until a final board 23 remains on the radial sawing device 18. This final board is of such thickness as to prevent the saw blade from coming in contact with the log clamping hooks 24 and 25 which are a part of the radial sawing device 18.

The log 10 may also have another section thereof cut as shown by section 12 in Figure 1 wherein three boards 26, 27, and 28 are initially cut from the quartered log, and then the remaining sector shaped section has a triangular heart section 29 cut therefrom so as to form a

truncated sector shaped section 30. This truncated sector shaped section 30 is then mounted on the radial sawing device 18, and successive cuts are formed in the sector shaped section 30 in the same manner as with the section 17.

Where an additional number of relatively wide boards are to be cut from the quartered section as shown by the quartered section 13, three vertical cuts 31 and 32 and 33 may be made through the quartered section, thereby forming three boards 34, 35, and 36. The opposite face of the reduced section 13 may also have two cuts 37 and 38 made therein parallel with the adjacent flat face of the initially quartered section thereby forming flat or rectangular boards 39 and 40. The remaining sector shaped section is then shifted on the saw carriage so as to permit the cutting of the heart section 41 from the remaining section. The heart section 41 is cut by means of a cut 42, which is made at an angle to the adjacent faces of the reduced section after the cuts 33 and 38 have been made therein.

The triangular heart sections 16, 29 and 41 are cut off for three reasons: first, to provide operating space for the log clamping hook 25. It may easily be seen that this purpose may also be served by chopping or otherwise cutting a notch in the heart corner of the log section at the point where the clamping hooks 25 will engage or end clamping may be used; second, to save the lumber contained in these heart sections, which has a value, and which would be cut up into sawdust if left attached to the remaining log section; third, to lessen the amount of wood through which the saw must cut in sawing the bevel boards, thus reducing the work of the saw and consequently the amount of power required.

The cutting off of varying numbers and thicknesses of vertical grain boards 26, 27, 28, 34, 35, 36, 39 and 40 is explained to show how any size log section may be made to fit the requirements for the sawing of any width bevel boards without loss or waste of timber and always securing an all vertical grain product.

In Figure 2 there is shown the conventional method hereinbefore used in the cutting of a comparatively large log. In this method the log is initially cut as indicated at 44 thereby removing a small slab 45. The log is then formed with another cut 46 removing a fairly thick slab 47 from which a rectangular board or plank 48 may be cut. The log is then formed with a further vertical cut 49 forming a relatively thick slab or board 50 which is subsequently cut as indicated by the lines 51 to form narrow boards.

After the cut 49 is made in the log, the log is turned at substantially right angles and a cut 52 is made in the log and a narrow slab 53 removed therefrom. A second cut 54 is made parallel to the cut 52 thereby removing a slab 55 from which a rectangular board or plank 56 may be cut. A further cut 57 is made in the log removing a plank 58 having parallel opposite faces and rounded edges. The plank 58 may then be cut along the lines 59 in a further sawing operation as to provide narrow boards or planks. An additional cut 60 is then made in the log parallel with the cut 57 removing a further fairly thick plank 61 which may be cut as along the lines 62 so as to form narrow boards of desired thicknesses. After the board or slab 61 has been cut from the log, the log is again turned through an arc of 90 degrees and moved past the saw with

a cut 63 being made in the log thereby removing a narrow slab 64.

A cut 65 is then made in the log parallel with the cut 63 removing a slab 66, and a rectangular board or plank 67 may then be cut from the slab 66. A further cut 68 parallel with the cut 65 is made in the log, removing a slab or plank 69 which may then be cut along the lines 70 so as to provide narrow planks or boards. A further cut 71 is made in the log parallel with the cut 68 thereby removing a plank or slab 72 which is adapted to be cut along the lines 73 so as to form narrow boards or planks.

The remaining portion of the log is then turned through a further arc of 90 degrees, and a cut 74 is made in the outer side of the log moving a slab section 75. Another cut 76 is made in the reduced log which is parallel with the cut 74 and which forms a fairly thin plank or board 77 from which a rectangular board or plank 78 may be formed. A further cut 79 is made through the log removing a slab or plank section 80 which is adapted to be cut along the lines 81 to form boards or planks of desired width and thickness. A further cut 82 is then made in the remaining portion of the log, thereby removing a rectangular plank 83 which may be cut along the lines 84 to provide planks or boards of desired width and thickness.

The remaining portion of the log will be substantially rectangular in transverse section, and this remaining portion may then be cut through the center as indicated by the line 85 and the two halves of the remaining block or plank may then be cut along the lines 86 and 87 to provide planks or boards of the desired width and thickness.

It will be noted from Figure 2 that the log therein shown is formed with a plurality of radially arranged or extending knots 88 which extend radially about the center 89 and that these knots 88 extend angularly with respect to the boards rather than substantially parallel with the opposite faces thereof.

It will be noted from the conventional method shown in Figure 2 that only a very small number of boards cut from the log have the grain substantially perpendicular to the opposite faces thereof. This procedure forms boards which are not desirable for certain purposes, particularly outer surfaces, and in a single log a considerable number of the boards cut therefrom are undesirable and will not meet building specifications calling for the grain of the lumber being disposed within a range of 25 degrees of the vertical.

In Figure 3 there is disclosed the new method of cutting a log which may have considerable knots 90 therein. The log 91 is initially quartered as shown in Figure 1 so as to provide quarter sections 92, 93, 94 and 95. The quarter sections 60 may then be cut parallel with one flat face thereof as by a cut 96 to form a flat board 97. The remaining sector shaped log section is then cut along an angular cut 98 so as to remove the heart section 99 therefrom. The remaining log section 100 is of truncated sector shape and is mounted on the radial sawing apparatus 18, where the radial cuts 101 may be made through the sector shaped section 100 to form a plurality of wedge shaped or bevelled boards 102.

It will be noted that when the bevelled boards 102 are cut from the sector shaped log 100, the knots 90 extend lengthwise or substantially parallel with the opposite faces thereof rather than extending substantially perpendicular to the op-

posite faces thereof, as the knots 88 in the conventional sawing method illustrated in Figure 2.

The hereinbefore described method of sawing or cutting a log provides not only radial cutting of the log, but also combines the radial cutting with the vertical or rectangular cutting of the log so that all of the boards cut from the log will be vertical grain and also a more nearly perpendicular or true vertical grain than is possible by the method heretofore used.

This radial cutting method also makes possible the building up of laminated timbers of any size which will have a true vertical grain throughout. This is done by gluing the desired number of boards together one on top of another, so that their thick and thin edges are alternately turned opposite.

The degree of bevel of the boards is changed by shifting the position in which the log section is held on the bevel sawing device. The changing of this position increases or decreases the radius of the circular arc in which the log section is moved as sawing progresses and consequently changes the degree of bevel of the faces of the boards.

What I claim is:

1. A method of cutting rectangular and beveled lumber from a quartered log having a pair of right angular flat faces which includes initially positioning the log with one flat face thereof horizontal and the other flat face thereof vertical and adjacent the saw, making at least one vertical cut parallel with said vertical face to thereby form

rectangular lumber, rotating the log to position the heart portion thereof innermost with respect to the saw and with the remaining right angular faces disposed at an obtuse angle to the vertical, cutting a triangular heart portion, again shifting the truncated quartered log to position one of the remaining right angular flat faces horizontal and the other of the right angular faces vertical with the axial center of the log grain closely adjacent the cutting line, and finally making a series of cuts from the periphery of the log toward the obtuse face formed by removal of the heart section with the log rocked toward the saw after each cut to thereby form beveled boards, each beveled board having the configuration of a truncated V in section.

2. A method of cutting rectangular and beveled lumber having the grain thereof substantially perpendicular to the opposite flat faces thereof from a quartered log provided with a pair of right angular faces which includes initially making at least one cut parallel with each flat face, cutting the log at an obtuse angle to said pair of flat faces to thereby remove a triangular heart portion and form a third flat face, and finally making a series of cuts from the periphery of the log toward the obtuse face formed by removal of the heart section substantially radically of the annular rings through the remaining log to thereby form beveled boards having the configuration of a truncated V in section.

EDWARD P. STAMM.
